UNITED STATES PATENT OFFICE.

SAMUEL CLARK, OF MARLBORO, MASSACHUSETTS.

ELECTRIC-LAMP HOLDER.

1,058,036.

Specification of Letters Patent.

Patented Apr. 8, 1913.

Application filed October 30, 1912. Serial No. 728,606.

To all whom it may concern:

Be it known that I, SAMUEL CLARK, a citizen of the United States, residing at Marlboro, in the county of Middlesex and State of Massachusetts, have invented new and useful Improvements in Electric-Lamp Holders, of which the following is a specification.

This invention relates to a holder for electric lamps.

The object of the invention is to provide a light and simple device capable of supporting an electric lamp in different positions and capable of being placed upon the top of a table or other horizontal surface and also capable of being attached to different articles of furniture, such as the backs of chairs, the frames of mirrors, and set at different angles thereon to throw the light in any desired or convenient direction.

The invention consists in an electric lamp holder such as hereinafter set forth in the specification and particularly as pointed out in the claims.

Referring to the drawings: Figure 1 is a plan view of a piece of sheet metal from which may be formed my improved electric lamp holder. Fig. 2 is a side elevation of the holder showing an electric lamp and its cord attached thereto as the same would be used when laid upon a stationary horizontal surface of a piece of furniture such as the top of a table. Fig. 3 is a side elevation of the holder showing the same attached to a suitable bracket or standard, said bracket or standard being adapted to rest upon a table or mantel. Fig. 4 is a side elevation of the holder with a lamp attached thereto showing the same in one position in full lines attached to the back rail of a chair, such as a rocker or Morris easy chair, and in dotted lines in the same figure the holder is shown in another position supported upon the same piece of furniture.

Like numerals refer to like parts throughout the several views of the drawings.

In the drawings, 6 is a piece of sheet metal illustrated in Fig. 1 in the shape in which it appears before being bent to form the holder 7. Said piece of sheet metal preferably has beveled corners 8 and has three holes 9, 10 and 11 punched therethrough. The hole 9 in the completed holder is for the purpose of suspending the holder from a nail or hook. The hole 10 is provided for the attaching means where-

by the electric lamp is clamped to the holder. 12 is a tongue stamped up from the sheet metal piece 6 and entirely detached from said sheet metal piece except at one end of 60 said tongue, viz, along the dotted line *a* (Fig. 1).

The piece of metal 6 is bent to form the holder 7 which, as a whole, consists of the U-shaped jaw 13, said jaw having a closed 65 end 14 and two legs 15 and 16, the sheet metal forming the jaw extending from the free end of the leg 16 backwardly therebeneath and extending backwardly beyond the closed end of the jaw forming a base 17. 70 The tongue 12 is bent upwardly from the base 17 and its free end rests against the closed end 14 of the U-shaped jaw to which it is preferably attached, either by solder or by any other suitable fastening means. 75

The closed end 14 of the jaw 13 is bent transversely thereof to form a rib 18 which extends between the legs 15 and 16 of the U for a short distance and toward the free ends of said legs.

An electric lamp 19 of usual design provided with a socket 20 is clamped by a bushing 21 to the tongue 12, the bushing 21 having a head 22 thereon which rests against the under side of the tongue 12 and also 85 having a screw-threaded shank 23 which projects through the hole 10 in the tongue 12 and has screw-threaded engagement with the socket 20 whereby said socket is clamped firmly to the tongue 12.

A flexible electric conductor 24 of the usual well known construction extends from the socket 20 along between the leg 16 and base 17 and through the hole 11, this hole preferably being located at the bent portion of the holder which connects the leg 16 to the base 17. By this construction it will be seen that the lamp is held firmly in position and that the electric conductor is protected and also held firmly in position 100 on the holder, and that said electric conductor is thus positioned so as to have no tendency to cause the holder to tip or become in any way displaced.

In Fig. 2 the holder is shown as resting 105 on its base in the position which it would occupy if placed on top of a table, mantel or the like.

In Fig. 3 the holder 7 is shown supported upon a bracket or standard 25. This bracket 110 has a transversely extending supporting arm 26 at the top of the standard 25 and

is also provided with a base 27 in order that the same may stand firmly upon a table, mantel or the like.

In Fig. 4 the holder is shown with its lamp supported upon a back rail 28 of a rocking chair or Morris chair and is shown in two positions. In the position shown in full lines the curved portion 29 of the holder rests upon the upper edge of the rail 28, while in the position shown in dotted lines the curved portion 30 rests upon the edge of the chair. The rib or transversely extending projection 18 divides these two curved portions 29 and 30 of the closed end 15 of the jaw one from the other and enables the jaw to be utilized on thick pieces as a support, such as, for instance, the cross-piece 26 of the bracket 25 and it also enables the holder to be firmly supported upon a 20 comparatively thin piece of furniture such as the rail 28 of a chair.

It will be seen that in the position assumed by the holder in full lines (Fig. 4) the leg 16 bears against the back of the rail 28 of the chair while in the position assumed in dotted lines (Fig. 4) the leg 15 bears against the front face of said portion of a chair, and the lamp is thus firmly held in different positions relatively to the person occupying the said chair, and thus the light can be thrown onto a book or paper which said person is reading at different angles and be placed nearer to or farther from said book, as the case may be.

Having thus described my invention, what I claim and desire by Letters Patent to secure is:

1. A holder for an electric lamp consisting of a piece of sheet material bent to form 40 a U-shaped jaw, said sheet material being extended from the free end of one leg of said jaw backwardly therebeneath to form a base and a tongue projecting from said base and adapted to have an electric lamp 45 fastened thereto.

2. A holder for an electric lamp consisting of a piece of sheet material bent to form a U-shaped jaw, said sheet material being extended from the free end of one leg of 50 said jaw backwardly therebeneath to form a base and a tongue projecting from said base against the closed end of said U-shaped jaw and constituting a brace, said brace adapted to have an electric lamp fastened thereto.

3. A holder for an electric lamp consisting of a piece of sheet material bent to form a U-shaped jaw, said sheet material being extended from the free end of one leg of 55 said jaw backwardly therebeneath to form

a base and a tongue integral with said base 60 and projecting therefrom against the closed end of said U-shaped jaw to which the free end of said tongue is fastened, said tongue constituting a brace adapted to have an 65 electric lamp fastened thereto.

4. A holder for an electric lamp consisting of a piece of sheet material bent to form a U-shaped jaw, said sheet material being extended from the free end of one leg of 70 said jaw backwardly therebeneath and 75 therebeyond to form a base and a tongue integral with said base and projecting from that portion of said base which extends beyond said U-shaped jaw into contact with the closed end of said U-shaped jaw, to 75 which closed end said tongue is fastened, said tongue constituting a brace adapted to have an electric lamp fastened thereto.

5. A holder for an electric lamp consisting of a piece of sheet material bent to form 80 a U-shaped jaw, said sheet material being extended from the free end of one leg of said jaw backwardly therebeneath to form a base, the closed end of said U-shaped jaw having a projection thereon extending inwardly between the legs of said U toward the free ends of said legs.

6. A holder for an electric lamp consisting of a piece of sheet material bent to form 90 a U-shaped jaw, said sheet material being extended from the free end of one leg of said jaw backwardly therebeneath to form a base, the closed end of said U being bent transversely thereof to form a rib extending 95 between the legs of said U toward the free ends of said legs.

7. A holder for an electric lamp consisting of a piece of sheet material bent to form a U-shaped jaw, said sheet material being extended from the free end of one leg of 100 said jaw backwardly therebeneath to form a base, a tongue projecting from said base against the closed end of said U-shaped jaw, a lamp socket, means to clamp said lamp socket to said tongue and an electric conductor extending from said lamp socket through 105 said tongue and thence extending between said base and the leg of said jaw adjacent thereto and through a hole provided in the bent portion of said holder connecting said 110 base and the leg adjacent thereto.

In testimony whereof I have hereunto set my hand in presence of two subscribing witnesses.

SAMUEL CLARK.
